UNITED STATES PATENT OFFICE.

OWEN TAYLOR AND CHARLES C. TAYLOR, OF HUNTINGTON, WEST VIRGINIA.

RADIANT HEATER.

Application filed March 3, 1923. Serial No. 622,546.

To all whom it may concern:

Be it known that we, OWEN TAYLOR and CHARLES C. TAYLOR, citizens of the United States, residing at Huntington, in the county 5 of Cabell and State of West Virginia, have invented certain new and useful Improvements in Radiant Heaters; and we do hereby declare the following to be a full, clear, and exact description of the invention, such as 10 will enable others skilled in the art to which it appertains to make and use the same.

The invention has relation to the type of heaters utilizing gaseous fuel and a radiant surface, which is rendered luminous or incandescent by the flame of the burning fuel. 15

The primary object of the present invention is the formation of a back wall and an open front for radiating the heat in one piece comprising units between which are formed 20 flues for the passage of the flame and gases, each of said units being formed of suitable refractory material and comprising a closed back, a front of open work, and a web connecting the front and back intermediate the 25 longitudinal edges thereof so as to form lateral or side spaces which, when the units are assembled, form flues for the passage of flame and hot gases.

Other objects and advantages will be apparent and suggest themselves as the nature 30 of the invention is understood.

While the drawings illustrate an embodiment of the invention it is to be understood that in adapting the same to meet different conditions and requirements, various changes in the form, proportion and minor details of construction may be resorted to without departing from the nature of the invention.

40 Referring to the accompanying drawings forming a part of the application:

Figure 1 is a front view of a radiant heater embodying the invention.

Figure 2 is a sectional view taken on the 45 line 2—2 of Figure 1.

Fig 3 is a sectional view taken on the line 3—3 of Figure 1, and

Figure 4 is a detail perspective view of one of the end units.

50 Corresponding and like parts are referred to in the following description and designated in the several views of the drawings by like reference characters.

The heater comprises a suitable frame 1 55 which may be of any finish and construction, depending upon the cost and design of the

heater. Within the frame 1 is arranged a back wall and a front radiant, a plurality of flues separating the radiant elements from one another and from the back wall, whereby to assure the heating of the radiant front to a glow or incandescent when the device is in active service. For convenience, the composite structure including the back wall and the front radiant comprise a plurality of elements of similar or like formation arranged perpendicularly with their vertical edges in contact. The outer half of the end units is preferably made solid, whereas the inner half corresponds to a half of any of the intermediate units. 60 65 70 75 80

The numeral 2 designates the end units which are of similar formation and 3 the intermediate units. Each of the units comprises a back 4, a radiant front 5 spaced from the back and a web 6 connecting the front and back intermediate their longitudinal edges whereby to form lateral or side spaces 7 which, when the units are assembled, form vertical flues for the flame and hot gases, 80 whereby the front is heated to a glow or incandescent. The back 4 is solid, whereas the front 5 is of open work which may be of any design most for ornamentation and to insure radiance of the heat. As shown, the 85 front of each unit comprises bars and diamonds having an alternate arrangement, opposite ends of the bars and opposite side portions of the diamonds projecting beyond opposite sides of the web 6 and when the units 90 are assembled, the ends of the bars and the points of the diamonds touch, whereby to form a radiant front of open work presenting an ornamental appearance and adapted to radiate the heat. The lower ends of the 95 units are recessed, as indicated at 8, to receive the burner pipe 9, the latter having nipples 10 in position and number to register with the vertical flues formed by the lateral or side spaces 7 when the units are assembled. 100

What is claimed is:

1. A radiant heater comprising a substantially solid back wall, a radiant front of open work spaced from the back wall, and 105 intermediate webs connecting the radiant front with the back wall and providing a plurality of flues, the heater being in sections having portions forming a front and being in contact. 110

2. A radiant heater comprising a plurality of separable units each of the units com-

prising a substantially solid back, a radiant front of open work, and a web connecting the radiant front and back forming lateral or side faces which, when the units are assembled, provide a plurality of flues the front of the different units being in contact at the side edges.

3. A radiant heater comprising a plurality of separable units, each of the units comprising a substantially solid back, a radiant front of open work, a web connecting the radiant front and back forming lateral or side spaces which, when the units are assembled,

provide a plurality of flues, the front of the different units being in contact at their side edges and a burner pipe disposed beneath the units and having nipples corresponding with the said flues. 15

In testimony whereof we affix our signatures in presence of two witnesses.

OWEN TAYLOR.

CHARLES C. TAYLOR.
